[57] CLAIM

The ornamental design for a handle for a hammer, substantially as shown and described.

DESCRIPTION

FIG. 1 is a front elevational view of a handle for a hammer showing my new design;

FIG. 2 is an edge elevational view thereof;

FIG. 3 is a top plan view thereof; and

FIG. 4 is a bottom plan view thereof.

FIG. 5 is a section taken on line 5—5 of FIG. 1.

The hammer head in FIGS. 1-4 is shown in broken lines for illustrative purposes only.

The dominant portion of the design is shown in full lines.
